United States Patent Office

Des. 216,101
Patented Nov. 25, 1969

216,101

WINDOW PANEL

Allan Landsman, 60—15 Calloway St.,
Corona, N.Y. 11368

Filed July 26, 1968, Ser. No. 12,912

Term of patent 14 years

Int. Cl. D25—02

U.S. Cl. D13—1

FIG. 1 is a front elevational view of the window panel embodying my new design;

FIG. 2 is a top plan view of the new design;

FIG. 3 is a side elevational view of the new design.

The broken lines shown in the drawing are for illustrative purposes only and form no part of the claimed design.

I claim:

The ornamental design for a window panel, substantially as shown and described.
